UNITED STATES PATENT OFFICE.

PETER HADNAGY, OF DETROIT, MICHIGAN.

RAIL-JOINT.

1,091,651.

Specification of Letters Patent. Patented Mar. 31, 1914.

Application filed December 20, 1913. Serial No. 808,010.

To all whom it may concern:

Be it known that I, PETER HADNAGY, a subject of the Emperor of Austria-Hungary, residing at Detroit, in the county of Wayne 5 and State of Michigan, have invented certain new and useful Improvements in Rail-Joints, of which the following is a specification, reference being had therein to the accompanying drawings.

This invention relates to rail joints, and the objects of my invention are, first, to provide simple and effective means for expeditiously connecting the confronting ends of rails without resorting to the use of bolts 10 with nuts; second, to provide a strong and durable rail joint that affords a large and substantial supporting area for the base flanges of rails; third, to provide inter-locking splice bars that prevent lateral and vertical displacement of rails, and fourth, to accomplish the above results by a mechanical construction that is inexpensive to manufacture and highly efficient for the purposes for which it is intended.

With the above and other objects in view, the invention resides in a novel construction, combination and arrangement of parts to be hereinafter specifically described and then claimed.

Reference will now be had to the drawing, wherein—

Figure 1 is a perspective view of the rail joint; Fig. 2 is a bottom plan of the rail joint; Fig. 3 is a horizontal sectional view 35 of the same, and Fig. 4 is a cross sectional view of the rail joint.

To connect the confronting or abutting ends of rails 1, I use splice bars 2 and 3, said splice bars having lateral base plates 4 and 5 respectively supporting the base flanges 6 of the rails. The splice bars 2 and 3 engage the webs 7 of the rails and support the heads thereof, said splice bars having the outer sides thereof provided with stiffening or reinforcing ribs 8. The ribs 8 are arranged at the ends and also intermediate the ends of the splice bars, the stiffening or reinforcing ribs at the ends of the bars merging into lateral extensions 9, which 45 are slotted, as at 10, whereby spikes or other fastening means can be employed for securing the lateral extensions to ties, sleepers or other supports (not shown). The meeting or adjoining edges of the base plates 4 and 5 are disposed at an angle, as best shown in Fig. 2, and these edges of the base plates

are provided with depending lugs 11 and 12, the lugs 11 being carried by the base plate 5 and the lugs 12 by the base plate 4. The lugs are arranged to extend over the 60 meeting edges of the base plates 4 and 5 and the lugs 11 are provided with pins 13 adapted to enter openings 14 provided therefor in the lugs 12. The arrangement of the lugs 11 and 12 is such that the base plates 4 and 65 5 can be placed together and then one shifted longitudinally of the other, whereby the pins 13 will engage in the lugs 12 and prevent lateral displacement of one splice bar 70 relatively to the other.

The splice bar 2 is provided with pins 15 that are riveted, brazed or otherwise mounted in openings provided therefor in the splice bar and are adapted to extend through slots or openings 16 formed in the 75 webs 7 of the rails. The pins 15 have offset portions 23 within the slots or openings 16, whereby the expansion of the rails 7 is limited to a certain degree at the confronting ends of the joint. The pins 15 are 80 provided with angularly disposed outer ends 17 which are slit, as at 18. The inner side of the splice bar 3 is provided with longitudinal grooves 19, said grooves merging into openings 20 in said splice bar. The 85 grooves 19 provide clearance for the angularly disposed ends 17 of the pins 15, when the splice bars are being assembled and said grooves serve as guides whereby the angularly disposed ends of the pins 15 will enter 90 the openings 20. The feathered or thin edges of the openings 20 are strengthened or reinforced by ribs 21 and after the splice bars have been placed in engagement with the rails, a split portion 22 of each pin is 95 bent into engagement with the ribs 21.

In assembling the parts of the rail joint, the openings 16 in the webs 7 of the rails are of a sufficient length to provide clearance for the angularly disposed ends 17 of the 100 pins 15, consequently the rails can be easily placed in engagement with the splice bar 2. The splice bar 3 can then be placed in position and shifted longitudinally of the rails until the angularly disposed ends of the pins 105 15 enter the openings 20. By then using a suitable tool the split portions 22 of the pins can be bent into engagement with the splice bar 3 to lock said splice bar relatively to the splice bar 2. Since the splice bar 3 110 can only be moved in one direction relatively to the splice bar 2, it is apparent that the

split portions 22 of the pins 15 will lock said splice bars against accidental displacement.

From the foregoing it will be observed that the splice bars can be easily cast and that their construction is such as to withstand a great weight of rolling stock to which they are subjected. The base plates of the splice bars prevent the confronting or abutting ends of the rails from breaking down, and it is thought that the utility of the rail joint will be apparent without further description.

One embodiment of my invention has been illustrated, but it is to be understood that the structural elements are susceptible of such variations and modifications as fall within the scope of the appended claims.

What I claim is:—

1. In a rail joint, the combination with rails, of splice bars, base plates carried by said splice bars and adapted to support the base flanges of said rails, depending lugs carried by the base plates of said splice bars, pins carried by some of said lugs and extending into the other of said lugs and adapted to prevent lateral displacement of said base plates, and transverse pins carried by one of said splice bars and adapted to extend through the webs of said rails and inter-lock with the other of said splice bars.

2. In a rail joint, the combination with rails, of splice bars engaging the sides of said rails, pins carried by one of said splice bars and adapted to extend through the webs of said rails, said pins having angularly disposed slit ends, the other splice bar having the inner side thereof provided with

grooves terminating in openings adapted to receive the ends of said pins, and said pins having slit portions thereof bent into engagement with the edges of the openings in said splice bar. 40

3. In a rail joint, the combination with rails having the webs thereof provided with openings, of splice bars engaging the sides of said rails, pins carried by one of said splice bars and extending into the other of said splice bars, said pins having off-set portions within the openings of the webs of said rails, and said pins having split ends 50 whereby a split portion of each pin can be bent into engagement with a splice bar to retain said bar in engagement with said rails. 45

4. In a rail joint, the combination with rails having the webs thereof provided with openings, of splice bars engaging the sides of said rails, one of said splice bars having the inner side thereof provided with longitudinal grooves terminating in openings, 60 ribs reinforcing edges of said openings, pins carried by the other of said splice bars and having off-set portions in the slots of said rails, and said pins having slit portions extending into the openings of said splice 65 bar with a slit portion of each pin bent into engagement with the rib of said splice bar.

In testimony whereof I affix my signature in presence of two witnesses.

PETER HADNAGY.
